UNITED STATES PATENT OFFICE.

LOUIS STEINBERGER, OF BROOKLYN, NEW YORK.

INSULATOR.

1,426,789.

Specification of Letters Patent. Patented Aug. 22, 1922.

Application filed January 28, 1922. Serial No. 532,387.

To all whom it may concern:

Be it known that I, LOUIS STEINBERGER, a citizen of the United States, and a resident of the borough of Brooklyn, county 5 of Kings, city and State of New York, have invented certain new and useful Improvements in Insulators, of which the following is a specification.

My invention relates to an insulator construction having particular reference to the type of strain members embedded therein.

This application is a continuation in part of my application Serial No. 212,340, filed January 17th, 1918, and it is filed in order 15 to cure some obvious discrepancies in the description and an error of the draughtsman in the drawing.

One of the objects of my invention is to provide strain members of such a construction as to prevent the concentration of heat in the central portion of the insulator body in which the strain members are embedded.

Another object of my invention is to so construct the strain members that the bridge 25 portions thereof will act as electro-static stress distributors.

Another object is to provide strain members in an insulating body which are so constructed that they will not only distribute electrical strains and stresses but 30 will also function as a uniform mechanical strain distributor.

Another object of the invention is to provide strain members having annular or ring shaped bridge portions, the opposing faces 35 of which are duplicates of each other and arranged to uniformly distribute electric stresses.

Other objects will appear from the subjoined specification and claims.

Referring to the drawings, Fig. 1 is a view partly in section and partly in side elevation of an insulator embodying my invention.

Fig. 2 is a similar view taken on line 2—2 of Fig. 1.

Fig. 3 is a perspective diagrammatic view with parts broken away showing the form, shape and disposition of the strain members 50 preparatory to molding them into the insulating body.

The insulating material may be of any suitable kind but I prefer to use the material known in the art as "Electrose," and 55 the remaining parts are formed of any suitable metal or alloys thereof.

Referring to the drawings, 10 is a body of insulating material which may be of any preferred shape but I have chosen to illustrate a body having a contour as shown 60 in Fig. 1 wherein the side of the body has projecting radially therefrom a central flange 11 of greater diameter than the two radially projecting flanges 12 and 13 at either end.

14 is an integral strain member, 15 is the embedded portion of a two part strain member having projecting legs 16 and 17, and 18 is the complementary portion of the strain member which is secured to the projecting ends 16 and 17 of the embedded portions by means of nuts 19 and 20 engaging screwthreads 21 and 21' and 22 and 22' on the respective ends of the portions 15 and 18 of the strain member, as well known in 75 this art.

The strain members are provided with bridge portions 30 and 31 which consist of rings 32 and 33, each of which is substantially circular in cross section and integrally secured to the embedded leg portions 34 and 35 and 36 and 37 of the respective strain members by means of offset arms 38, 39, 40 and 41 as shown. The strain members are interlocked one with the other so 80 that in case the insulating material should be destroyed the line will not fall to the ground, and they are so situated with respect to each other that the respective rings of the bridge portions of the strain members 90 will be oppositely disposed to each other in the central portion of the body of insulating material, the distance between the respective rings being less than the distance between the ring of one strain member 95 and the legs of the other strain member.

The special functions of the ring portions of the strain members are to act as electrical stress or strain distributors, and at the same time act as uniform mechanical 100 strain distributors. Because of the open or skeleton construction due to the oppositely disposed ring portions, the danger to the insulating material arising out of heat concentration in the central portion of the 105 insulating body is greatly lessened.

The opposing faces of the rings are curved in cross section or convex to each other and each ring is a duplicate of the other so that each point on the opposing surface of one ring is directly opposite a corresponding point on the surface of the other. The elec-

tric stresses or lines of force emanating from the rings are therefore dispersed throughout the body of insulating material lying between the two rings and do not tend to concentrate in sections between the rings. As the legs 34, 35, 36 and 37 are so positioned on their respective rings, as clearly shown in the drawings, that they pass the opposing rings at a greater distance than the distance between the opposing surfaces of the ring, there is no appreciable tendency towards the setting up of stresses between the rings and the legs of the opposing ring.

The distance between the opposing rings is indicated in the drawing by the letter X, and the distance between the ring of one strain member and the respective legs of the other strain member by the letter Y, and, as above stated, the distance X is less than either of the distances Y, the distances Y being substantially equal to each other.

As illustrated perspectively in Fig. 3, the offset portions of the bridges of the strain member are curved at 50, 51, 52 and 53 in order to cause the ring or electro-static stress distributor portions only to be positioned on the central part of the body of the insulating material. When thus offset the electrical strains and stresses will be more effectually distributed between the rings in the central portion of the insulating body, thus preventing the concentration of heat therein.

The distance between the bridge or ring portions is determined in accordance to the voltage to which the strain member is to be subjected. As will be readily understood, the greater the space between the rings or bridge portions of the strain members the greater will be the insulation value of the insulator. In any case, however, the distance from a ring to the leg of the opposing ring should be greater than the distance between the rings.

As changes of construction could be made within the scope of my invention, it is intended that all matter contained in the above description or shown in the accompanying drawings shall be interpreted as illustrative and not in a limiting sense.

Having thus described my invention what I claim as new and desire to secure by Letters Patent is:

1. In a device of the kind described, an insulating body, interlocked strain members embedded therein, each of said strain members embodying leg portions and a stress distributing ring portion therebetween, the said leg portions being rigidly secured to and bridged by the said ring portion, the ring portion of one of said strain members being disposed opposite to the ring portion of the other strain member, each of said ring portions being circular in vertical cross section, the ring portion of one strain member be-

ing insulated from the leg portions of the other strain member.

2. In a device of the kind described, interlocking strain members, each of said strain members having leg portions and a bridge portion embodying a stress distributing ring, the said stress distributing rings being similarly shaped, the said leg portions of each strain member being integral with and offset from the ring portion and disposed outside thereof, the respective rings having curved surfaces disposed opposite to each other.

3. In a device of the kind described, an insulating body, a strain member embedded therein, said strain member having leg portions and a stress distributing bridging element embodying a ring shaped portion, the leg portions being connected to and offset from said ring shaped portion and disposed near the periphery of the insulating body, the ring portion being removed from and located between the said leg portions of the strain member, the ring portion having a curved cross sectional surface.

4. In a device of the kind described, interlocking strain members, each strain member having leg portions connected by a stress distributing bridge portion therebetween, the said bridge portions each including a ring shaped member the said ring shaped members being duplicates of each other and round in vertical cross section, the ring portion and leg portions of one strain member being insulated respectively from the ring portion and the leg portions of the other strain member.

5. In a device of the kind described, an insulating body, a strain member, said strain member consisting of a substantially U-shaped portion embedded in said insulating body, the legs thereof projecting out of the insulating body and being connected to each other by a stress distributing ring portion of less diameter than the distance between the leg portions, the said ring portion being round in vertical cross section.

6. In a device of the kind described, strain members, each strain member having leg portions and a bridge portion embodying a stress distributing ring, the respective rings having curved surfaces disposed directly opposite to each other and situated wholly between the said leg portions.

7. In a device of the kind described, strain members, each strain member being provided with leg portions and a ring shaped bridge portion therebetween embedded entirely within the body of insulating material, each of said bridge portions having a curved surface, the curved surface of one bridge portion directly facing the curved surface of the other bridge portion, the two bridge portions being spaced apart by a portion of the insulating material.

8. In a device of the kind described, a

body of insulating material, strain members embedded therein, each strain member including a stress distributing ring shaped bridge portion provided with a curved surface, the respective strain members also having leg portions extending from the respective ring portions out of the insulating material in opposite directions, the legs being spaced apart and those connected to each 10 ring passing outside of the other ring.

9. In a device of the kind described, a body of insulating material, strain members therefor, a stress distributing ring entirely embedded in the body of insulating material 15 attached to each strain member, each ring being provided with a stress distributing curved surface, the said stress distributing curved surfaces being uniformly positioned with respect to each other and disposed 20 directly opposite to each other, the adjacent directly opposing portions of said surfaces being duplicates of each other.

10. In a device of the kind described, a body of insulating material, strain members 25 therefor, each strain member including a stress distributing ring entirely embedded in the body of insulating material, each of said rings being circular in vertical cross section, the stress distributing surface of one ring 30 being disposed directly opposite to the stress distributing surface of the other ring, the adjacent directly opposing portions of said surfaces being duplicates of each other.

11. In a device of the kind described, interlocking strain members, each strain member including a bridge portion, each bridge portion being similarly shaped and embodying a stress distributing ring, and leg por-

tions integral with and offset from the said ring outside thereof.

12. In a device of the kind described, an insulating body, a strain member connected thereto, said strain member having leg portions and a stress distributing bridging element therebetween embodying a ring-shaped portion, the leg portions being connected to and offset from said ring-shaped portion and disposed near the periphery of the insulating body, the ring portion being removed from and located between the said 50 leg portions of the strain member.

13. In a device of the kind described, a body of insulating material, strain members connected thereto, each strain member including a stress distributing ring shaped 55 bridge portion, the respective strain members also having leg portions extending from the rings in opposite directions, the legs being spaced apart and those connected to each ring passing outside of the other 60 ring, the said bridge portions being disposed directly opposite to each other.

14. In a device of the kind described, an insulating body, a strain member consisting of a substantially U-shaped portion connected to the said insulating body, the legs thereof being connected to each other by a stress distributing ring portion of less 65 diameter than the distance between the leg portions.

In witness whereof, I have hereunto set my hand at the borough of Manhattan, city and State of New York, this 23 day of January, 1922.

LOUIS STEINBERGER.
